UNITED STATES PATENT OFFICE.

ISAAC N. LEWIS, OF MONTCLAIR, NEW JERSEY.

CARTRIDGE MAGAZINE.

Application filed January 24, 1919. Serial No. 272,950.

To all whom it may concern:

Be it known that I, ISAAC NEWTON LEWIS, a citizen of the United States of America, residing at 1 Russell Terrace, Montclair, in the county of Essex and State of New Jersey, have invented certain new and useful Improvements in Cartridge Magazines, of which the following is a specification.

This invention relates to an improved 10 cartridge magazine for firearms, and particularly to a cartridge magazine for use with automatic or semi-automatic firearms of the light machine gun type, although it is not limited in this respect.

15 Cartridge magazines of the character to which the present invention is related, have been arranged to contain either a single row of cartridges or a double row thereof. The single row magazine necessarily provides for 20 a uniform feeding of the cartridges by the actuating mechanism of the firearm, from the magazine into the gun barrel, as the cartridges are moved upwardly in a single vertical plane and successively occupy the 25 same position at the upper end of the magazine. The double row magazine, while it greatly increases the capacity of the magazine and the number of rounds which may be fired without reloading, does not permit 30 of such uniform and accurate feeding of the cartridges, since the latter have to be fed by the actuating mechanism of the firearm, first from one lateral position or row and then from the other, such lateral positions or rows 35 being at opposite sides of the vertical longitudinal median plane of the firearm. While therefore the double row magazine possesses the advantage of holding a considerably increased number of cartridges or rounds, the 40 single row magazine possesses the advantage of uniformity of feeding from the magazine to the gun barrel.

The object of the present invention is to provide an improved form of magazine of 45 the double row type from which the cartridges may be fed with absolute uniformity and accuracy into the chambered end of the gun barrel. That is to say, the improved magazine will possess the advantages of both 50 the single row and double row types of magazine.

The invention consists in a cartridge magazine, which comprises a casing constructed to hold two parallel rows of cartridges in staggered relation with the cartridges of each row in contact with each

other and with the cartridges of the other row and in contact with the adjacent sides of the casing, and rigidly constructed at the upper end thereof to position the uppermost 60 cartridge in the magazine in the central longitudinal plane thereof, and cartridge supporting and elevating means within said casing and in contact with the lowermost cartridge of each row thereof. 65

It will thus be seen that as each cartridge is moved upwardly, to take the place of a cartridge removed from the magazine by the actuating mechanism of the firearm, it is positioned in exactly the same position as 70 the preceding cartridge occupied, and in exactly the same relation to the actuating mechanism of the firearm and to the chambered end of the gun barrel. The cartridges will thus follow the same path when moved 75 by the actuating mechanism into the end of the gun barrel, this path lying in the vertical longitudinal plane passing through the axis of the gun barrel. By the use of this magazine therefore complete uniformity 80 and accuracy in the feeding of the cartridges from a double row thereof is obtained, with consequent increase in the efficiency of operation of the firearm.

Preferably, the side walls of the magazine 85 at their uppermost extremities are shaped to receive and hold between them a single cartridge and to position said cartridge centrally of the magazine, and furthermore, the said side walls may have the upper portions 90 thereof formed so that they positively guide the cartridges alternately from the two rows thereof into the central longitudinal plane of the magazine.

Various other distinctive features of the 95 improved magazine will be more fully described hereinafter, and clearly pointed out in the appended claims.

In the accompanying drawings, one form of magazine constructed in accordance with 100 the present invention is illustrated, and is shown applied to an automatic firearm of the light machine gun type.

In these drawings:—

Figure 1 is a longitudinal sectional view 105 of the body or receiver of the gun, within which body the actuating mechanism is located, the magazine applied to this body being also shown in longitudinal section;

Figure 2 is a cross sectional view taken 110 on the line 2—2 of Figure 1, looking toward the muzzle of the gun and showing the ar-

angement of the cartridges in the magazine;

Figure 3 is an outside elevational view of the cartridge magazine;

5 Figure 4 is a plan view of said magazine;

Figure 5 is a sectional plan view of the magazine showing the arrangement of the cartridges therein, and

10 Figure 6 is a detailed perspective view of the spring actuated follower of the magazine.

Figure 7 is an outside view on an enlarged scale of a magazine substantially similar to that illustrated in Figure 3, but 15 differing therefrom in capacity and in constructional details;

Figure 8 is a cross-sectional view of the magazine shown in Figure 7, taken approximately on the line 8—8 of said figure;

20 Figure 9 is an elevation of the rear end of the magazine;

Figure 10 is a view of the magazine taken from below;

25 Figure 11 is a partial side sectional elevation of the magazine, showing a smaller number of cartridges than in Figure 8;

Figure 12 is a sectional plan view of the magazine, and

30 Figure 13 is a detail view of the follower. For the purpose of illustration only and without any intention of limiting the application of the improved magazine thereto, said magazine is illustrated in Figure 1 as applied to a shock-operated automatic fire-35 arm of the character described in Patent 1,430,661, Oct. 3, 1922. This firearm, of course, forms no part of the present invention but its arrangement and operation will be briefly mentioned in order to clearly 40 show the manner of application of the magazine thereto, and the manner in which the cartridges are successively removed from said magazine into the chambered end of the gun barrel.

45 When the breech block or bolt 1 is in the rearward position indicated, and pressure is applied to the trigger 2, a shoulder 3 on the latter engages and raises the forward end of the sear 4, depressing the rear end 50 of the sear and releasing the same from a notch in the bolt. When the bolt is thus released the return spring 5 moves the operating member 6 forwardly, and the post 7 of said member being in engagement with 55 an inclined surface of a cam slot 8 in the bolt, the latter moves forwardly with the post and operating member, being prevented from rotating by a projection 9 engaging a slot 10 in the body 11 of the gun.

60 As the parts advance in this relationship the lower front edge of the bolt engages the head of a positioned cartridge 12 and forces the same in advance of the bolt into the chambered end of the gun barrel 13. When 65 the bolt engages the forward end of the

barrel the projection 9 engages a circumferential slot in the body and permits the bolt to be rotated by the post 7 co-acting with the slot 8 to bring lugs on the bolt in front of lugs 14 on the body so as to prevent rearward movement of the bolt when the cartridge is fired. The operating member 6 and post 7 then advance still further to carry the firing pin 15 forwardly to strike the head of the cartridge and fire 75 the same. The gases of discharge resulting from the firing of the cartridge are utilized in the manner described in application No. 263,824 filed November 23rd, 1918, to produce a shock or pressure impulse which is imparted to the forward end of a piston 16, the rear end of which is indicated in Figure 1, this piston being connected by a rod 17 to the operating member 6. This member is thus moved rearwardly by the shock or pressure impulse produced, and during such movement first retracts the firing pin 15, then co-acts with the cam slot 8 to rotate the bolt to release the lugs thereon from the lugs 14, and then engages the rear end of this slot to return the bolt to its rearmost position as indicated in Figure 1, in which position it is again held by the sear, which has in the meantime been returned to its initial position.

With the trigger and sear having the relative positions indicated in Figure 1, pressure of the trigger as already described, permits the firing of an individual round, but as clearly described in the companion application above mentioned, the trigger pin 18 has an eccentric portion whereby on rotation of this pin the trigger may be moved slightly rearwardly to bring the shoulder 3 farther beneath the forward end of the sear 4 so that on applying pressure to the trigger and maintaining such pressure, the sear may be held in inoperative position so that the bolt on its return movement is not held thereby but is again advanced by the return spring to fire the successively positioned cartridge in the manner described, the operation being repeated until any desired number of cartridges within the capacity of the magazine has been fired.

On each return movement of the bolt the empty shell is extracted by extractors on the forward end of the bolt and is ejected by suitable ejecting mechanism through an aperture 19 in the body.

Referring now to the particular form of magazine illustrated in the drawings, it will be seen that this magazine consists of a casting 20 the side walls of which are substantially parallel and arranged at such a distance apart that the cartridges 12 placed therein form a double row with the cartridges in staggered contacting relation as indicated in Figures 2, 4 and 5. The lowermost cartridges rest upon a platform or fol-

- lower 21 which is pressed upwardly by means of the spring 22 of usual form. The platform 21 (see Figures 2 and 6) has a portion thereof pressed upwardly at 23 to support one of the lowermost cartridges in its staggered relation to the other thereof, and to enable the upward pressure of the spring to be positively and directly imparted to both rows of cartridges, so that
- 10 the group of cartridges is moved upwardly as a unit, and jamming of said cartridges in the magazine is prevented. The side walls of the magazine are preferably formed with inwardly projecting ribs 24 with which the
- 15 cartridges engage, as shown in Figure 5, these ribs reducing the extent of contact of the cartridges with the magazine walls and facilitating the upward movement of the cartridges under the action of the spring.
- 20 The side edges of the platform or follower 21 may engage these ribs, or they may be notched to receive the ribs which then serve to guide the follower in its upward and downward movements.
- 25 The side walls of the magazine at the upper ends thereof are inclined or converge toward each other as indicated at 25, and the extremities of these walls are curved as indicated at 26, to enable them to contact with and fit partially around the surface of a single cartridge 12. The centre of curvature of the extremities 26 lies in the longitudinal median plane of the magazine. Thus when the uppermost cartridge 12, Figure 2,
- 30 35 is removed from the magazine by the bolt 1, the next lower cartridge 12' is pressed upwardly into contact with the inclined or converging end 25 of the side wall of the magazine and is guided by said inclined end toward the longitudinal median plane of the magazine, and is finally pressed by the cartridge 12² beneath it into contact with the curved extremities 26 of the side walls, being positioned by said walls for engagement and
- 40 45 removal by the bolt. When the cartridge 12' so positioned is removed by the bolt, the cartridge 12² is similarly pressed upwardly and guided by the inclined or converging end of the opposite side wall of the magazine into position between the extremities 26, the operation being repeated at each removal of a cartridge. Thus cartridges are positioned for engagement by the bolt, alternately from the two rows of cartridges in the magazine,
- 50 55 and it will be noticed that each cartridge engaged by the bolt occupies identically the same position as its predecessor occupied, and follows the same path as its predecessor when forced by the bolt into the chambered end of the barrel, this path lying at all times in the vertical longitudinal median plane of the gun. Thus absolute uniformity in the feeding of the cartridges to the gun barrel is obtained with a double row magazine, or
- 60 65 in other words, the advantageous uniform feeding action obtained with a single row magazine is obtained with the use of a double row magazine, instead of the alternate feeding first from one side and then from the other obtained with the usual double row magazines. This uniformity in the feeding of the cartridges necessarily increases the efficiency of the gun in operation.
- 70 The cartridges might be guided into place between the extremities 26 by pressing the metal of the side walls inwardly a greater distance at the upper ends of the ribs 24, to form inclined or converging ribs, from a point below the inclined ends 25 to said extremities 26, these converging ribs then guiding the cartridges into place. These inclined or converging ribs might be used with a magazine having plain side walls, or the upper end of the magazine might be otherwise formed to ensure the cartridges being guided alternately from the two rows thereof into the longitudinal median plane of the magazine.
- 75 80 The forward portions of the side walls of the magazine converge toward each other, as indicated in Figure 5, following substantially the curvature of the bullets 27, the platform or follower 21 being correspondingly shaped at its forward end.
- 85 90 It will be noted from Figures 1, 3 and 4, that the curved extremities 26 of the side walls of the magazine extend substantially half way from rear to front of the magazine and their extreme forward edges contact with each cartridge during its movement by the bolt, to hold its rear end or head in the magazine until the bullet 27 is guided by the inclined surface 28 on the body, into the chambered end of the barrel. The cartridge is then released from said extremities, and by the movement of the succeeding cartridge into place, is thrown upwardly slightly to bring it into substantial alignment with the axis of the barrel.
- 95 100 The spring 22 is preferably secured to the follower 21 by means of lugs or ears 29 bent over at the side edges of the follower, and between which lugs and the follower the upper leaf of the spring is inserted. These lugs may be formed on the follower by rolling or pressing down the forward side edges thereof so as to shape the forward end of the follower and at the same time form the lugs, between which and the follower the forward end of the upper leaf of the spring 105 is inserted. The spring may be similarly secured to the bottom plate 30 although it may of course be secured to the follower, or to the bottom plate, in any other convenient way.
- 110 115 The bottom plate 30 may be soldered or otherwise permanently secured to the walls of the magazine, or said plate may be removably secured thereto by suitable catches on said plate or said walls, which are releas-
- 120 125
- 130

able by an operator equipped with a suitable tool, to permit the follower and spring to be removed and replaced when desired.

The front and rear walls of the magazine are preferably slightly curved as indicated in Figures 1 and 3, to allow for the curvature or inclination of the front and rear ends of the group of cartridges due to the slight tapering of the walls thereof. The upper edge of the rear wall is curved coincidentally with the wall of the bore 31 in which the bolt 1 slides, and the extremities 26 hold the cartridges so that the heads thereof project just sufficiently above said curved edge to enable them to be engaged by the bolt. The cartridges are inserted in the magazine through the opening in the top thereof in the usual manner, and the magazine may be constructed to hold five, ten, fifteen, twenty or any other suitable number as may be desired.

The magazine is inserted in a recess formed in the lower part of the body, in communication with the lower bore 31 therein, the forward wall of the magazine having an aperture adapted to engage over a pin 32 in the forward wall of the recess, and the rear wall co-acting with a latch 33 which extends through an aperture in the wall 34 into a notch or aperture 35 in the said rear wall, which wall may be slightly pressed out above the notch, as indicated to more securely co-act with the latch.

The latch 33, as shown in Figure 1 is mounted in a recess in the forward end of the guard 35^a of the trigger mechanism, the latch having tongues 36 on its side faces co-acting with corresponding grooves in the walls of said recess, and being pressed forwardly by a spring 37. The forward and rearward movements of the latch are limited by a pin 38 co-acting with a groove or recess 39 in the upper face of the latch. By rearward pressure against the rear curved end 40 of the latch, which is located in close proximity to the trigger 2, the forward end of the latch may be released from the notch 35, thus permitting the magazine to fall or be removed from the recess in the body. Thus without substantially changing the position of the hand in firing, an empty cartridge magazine may be released from the firearm and a loaded magazine substituted in place thereof by means of the other hand, enabling the reloading of the firearm to be effected with extreme rapidity and ease.

In Figures 7 to 13, is illustrated another form of magazine which while operating to position cartridges alternately from a double row in the median plane of the magazine as in the form already described, is constructed and arranged so that it may be readily and economically manufactured in large quantities.

The magazine in this form comprises two

similar casing portions 41 and 42, each consisting of a side wall and front and rear end wall portions 43, which are curved as indicated in Figures 7 and 11 to allow for the curvature or inclination of the front and rear ends of the group of cartridges. The side wall of each casing portion 41, 42, is formed at the upper end thereof with an inclined surface 44 terminating in a curved extremity 45, and is also provided with inwardly projecting ribs 46, and is pressed inwardly at 47 to provide the reduced forward portion of the magazine. The ribs 46 are of substantially semi-circular cross section, and it will be noted from Figure 8 that they are pressed inwardly to a greater extent at their upper ends to provide curved guiding surfaces terminating at the extremities 45.

The distance between the end wall portions 43 of the casing portion 41 is less than the distance between the end wall portions 43 of the casing portion 42, so that the first mentioned portions 43 fit within the portions 43 of casing portion 42, as will be clear from Figure 12, and the respective end wall portions are secured together in this overlapping relationship by any suitable securing means. As illustrated, these portions are secured together by aperturing the same at a number of spaced points 48, four as shown in Figure 9, and turning the metal at the edges of the apertures of one end portion outwardly around the edges of the apertures of the other end portion as clearly shown at 49 in Figure 12, this method of securing the parts being quick and effective and avoiding the necessity for the use of additional securing means.

The side walls of the casing portions at the lower ends thereof are provided with inwardly turned lugs 50, Figure 10, which together with the lower ends of the ribs 46 form guides to permit the bottom plate 51 to be slid into place. This plate 51 is provided with lugs 52 at its front and rear ends adapted to be bent up into correspondingly shaped recesses 53 in the lower ends of the end walls 43 of casing portion 42, see Figure 9. The bottom plate is thus easily placed in position and is firmly held in place by the lugs 50 and 52. By bending down the front lug 52, the bottom plate may be readily removed.

The follower 54 is of similar construction to the follower of the magazine previously described, being provided with an upwardly pressed portion 55, Figures 8 and 13, and with downwardly bent side lugs 56, whereby the spring 57 may be connected to the follower. The spring 57 is formed from resilient wire and its upper end is adapted to be slid between the lugs 56 of the follower, one of the latter being recessed at 58 to receive a bend 59 in the

spring to properly locate the latter relatively to the follower. The follower may be provided with notches 60, to receive the ribs 46 of the casing portions.

It will be seen from Figure 8, that when the casing portions 41 and 42 are secured together the distance between the ribs 46 is such that two rows of cartridges may be arranged within the magazine, with the cartridges of each row in contact with each other, in contact with the cartridges of the other row, and in contact with the ribs 46, and that these cartridges will be smoothly and easily elevated to the upper end of the magazine by the follower 54 and spring 57. The cartridges will be guided in succession, alternately from the two rows, by the curved upper ends of ribs 46, into place between the curved extremities 45 of the side walls, the cartridges being thus positioned in succession in the median vertical plane of the magazine.

While particular forms of magazine have been described above in detail, it is to be understood that the invention is not restricted to these particular forms of magazine, but that the form and construction may be varied as may be desirable or necessary to suit the particular form of firearm to which the magazine is to be applied, or for other reasons. The essential feature of the invention is that the magazine is so constructed that the cartridges from a double row thereof may be successively positioned in the central longitudinal plane of the magazine so that these cartridges may be uniformly fed from the magazine into the chambered end of the gun barrel by the actuating mechanism of the firearm.

Having now particularly described and ascertained the nature of my said invention and in what manner the same is to be performed, I declare that what I claim is:—

1. A cartridge magazine, comprising a casing having a width sufficient to hold two parallel rows of cartridges in staggered relation with the cartridges of each row in contact with each other and with the cartridges of the other row, and at its upper end symmetrically decreased in width to form opposite guiding surfaces terminating in extremities shaped to partially surround and contact with opposite side portions of a cartridge to exactly position and rigidly hold said cartridge centrally of the casing, and cartridge elevating and supporting means within said casing, the guiding surfaces alternately acting, at successive elevations of said cartridges, to move the uppermost cartridge inwardly upon the uppermost cartridge of the other row, and the latter under the action of said elevating means directly pressing said uppermost cartridge into place between the extremities of the casing.

2. A cartridge magazine, comprising a casing having side walls spaced apart a distance to hold between them two parallel rows of cartridges in staggered relation with the cartridges of each row in contact with each other and with the cartridges of the other row, said side walls being provided with upper extremities curved to conform to the exterior curvature of a cartridge to position said cartridge in the central longitudinal plane of the casing, and being provided below said extremities with inwardly and upwardly converging surfaces alternately engaging the uppermost cartridge of the adjacent row to guide said cartridge into position between said extremities, and cartridge supporting and elevating means within said casing operating at each elevating movement thereof to press the uppermost cartridge, guided by the adjacent converging surface, directly from the corresponding row thereof into position between the upper curved extremities of the side walls.

3. A cartridge magazine, comprising a casing having a width sufficient to hold two parallel rows of cartridges in staggered relation with the cartridges of each row in contact with each other and with the cartridges of the other row, and having its upper end symmetrically decreasing in width to receive and centrally position a single cartridge, the side walls of said casing adjacent the upper ends thereof being provided with inwardly projecting guiding ribs inwardly and upwardly converging from the wider to the narrower portion of the casing to alternately guide the uppermost cartridges of said rows into central position in the narrower portion of the casing, and cartridge supporting and elevating means within said casing.

4. A cartridge magazine, comprising two side walls spaced apart a distance to hold between them two parallel rows of cartridges in staggered relation, with the cartridges of each row in contact with each other and with the cartridges of the other row, said side walls being parallel excepting at the upper ends thereof which converge symmetrically toward each other and are provided at the rear portions thereof above said converging portions with extremities curved to conform to the exterior curvature of a cartridge to firmly hold between them a single cartridge in the central longitudinal plane of the magazine, a front wall permitting forward movement of the uppermost cartridge, and a rear wall engaging said cartridge to prevent rearward movement thereof.

5. A cartridge magazine, comprising two side walls spaced apart a distance to hold between them two parallel rows of cartridges in staggered relation, with the cartridges of

- each row in contact with each other and with the cartridges of the other row, said side walls being parallel excepting at the upper ends thereof which converge symmetrically toward each other and are provided at the rear portions thereof with extremities shaped and spaced apart a distance to firmly hold between them a single cartridge in the central longitudinal plane of the magazine, 5 inwardly projecting guiding ribs on said side walls at their upper ends, said ribs converging to guide the cartridges into position between said extremities, a front wall permitting forward movement of the upper 10 most cartridge, and a rear wall engaging said cartridge to prevent rearward movement thereof.
6. A cartridge magazine, comprising a casing having side walls provided with upwardly extending substantially parallel ribs, the inner surfaces of the opposing ribs being spaced apart a distance to hold between them two parallel rows of cartridges in staggered relation with the cartridges of each 15 row in contact with each other and with the cartridges of the other row, said side walls at their upper ends converging inwardly and upwardly and terminating in curved extremities adapted to receive and centrally position a single cartridge, and said ribs at their upper ends being curved inwardly and upwardly to guide the cartridges alternately from said rows into position between said extremities, and cartridge supporting and elevating means within said casing.
7. A cartridge magazine, comprising two similar but reversed casing portions each having a side wall and front and rear end walls, with the front end walls and the rear 20 end walls of the two portions respectively overlapping and secured together to space said side walls a distance to hold between them two parallel rows of cartridges in staggered relation with the cartridges of each 25 row in contact with each other and with the cartridges of the other row, said side walls at their upper ends converging inwardly and upwardly to hold and centrally position a single cartridge between their extremities, and at their lower ends being provided with inwardly extending lugs, a bottom plate supported by said lugs and itself provided with lugs bent up to engage the front and rear end walls of the casing portions, and cartridge supporting and elevating means within said casing.
8. A cartridge magazine, comprising two similar but reversed casing portions each having a side wall and front and rear end walls, with the front end walls and the rear 30 end walls of the two portions respectively overlapping and secured together to space said side walls a distance to hold between them two parallel rows of cartridges in staggered relation with the cartridges of each 35 row in contact with each other and with the cartridges of the other row, said side walls at the upper ends thereof converging inwardly and upwardly to hold and centrally position a single cartridge between their extremities, and cartridge supporting and elevating means within said casing.
9. A cartridge magazine, comprising two similar but reversed casing portions each having a side wall and front and rear end walls, with the front end walls and the rear 40 end walls of the two portions respectively overlapping and secured together to space said side walls a distance to hold between them two parallel rows of cartridges in staggered relation with the cartridges of each 45 row in contact with each other and with the cartridges of the other row, said side walls at the upper ends thereof converging inwardly and upwardly to hold and centrally position a single cartridge between their extremities, and cartridge supporting and elevating means within said casing.

In testimony whereof I affix my signature in presence of two witnesses.

ISAAC N. LEWIS.
